[57] CLAIM

The ornamental design for an upright chair, as shown and described.

DESCRIPTION

FIG. 1 is a perspective view of a first embodiment of an

upright chair showing my new design in the form of a dining chair;

FIG. 2 is a front perspective view of the upright chair of FIG. 1;

FIG. 3 is a back perspective view of the upright chair of FIG. 1;

FIG. 4 is a first side perspective view of the upright chair of FIG. 1;

FIG. 5 is a second side perspective view of the upright chair of FIG. 1;

FIG. 6 is a top perspective view of the upright chair of FIG. 1;

FIG. 7 is a bottom perspective view of the upright chair of FIG. 1;

FIG. 8 is a perspective view of a second embodiment of an upright chair showing my new design in the form of a lounge chair;

FIG. 9 is a front perspective view of the upright chair of FIG. 8;

FIG. 10 is a back perspective view of the upright chair of FIG. 8;

FIG. 11 is a first side perspective view of the upright chair of FIG. 8;

FIG. 12 is a second side perspective view of the upright chair of FIG. 8;

FIG. 13 is a top perspective view of the upright chair of FIG. 8; and,

FIG. 14 is a bottom perspective view of the upright chair of FIG. 8.

FIGS. 2 through 7 have been shown on an enlarged scale with respect to FIG. 1 and FIGS. 9 through 14 have been shown on an enlarged scale with respect to FIG. 8.
